(57) **CLAIM**

The ornamental design for a fender for electric vehicle, as shown and described.

DESCRIPTION

FIG. 1 is a top, rear perspective view of the new design for a fender for electric vehicle;

FIG. 2 is a top, front perspective view thereof;

FIG. 3 is a top perspective view thereof;

FIG. 4 is a bottom perspective view thereof;

FIG. 5 is a left side view thereof;

FIG. 6 is a right side view thereof;

FIG. 7 is a front view thereof;

FIG. 8 is a rear view thereof;

FIG. 9 is a top view thereof; and,

FIG. 10 is a bottom view thereof.

The broken lines shown in the drawings illustrate portions of the fender for electric vehicle that form no part of the claimed design.

The shading lines shown in the drawings represent the approximate three-dimensional contour of the design, and are not intended to indicate surface decoration.
